SWAN M. AKEYSON, OF LONG BEACH, CALIFORNIA

ROTARY UNDERREAMER

Application filed November 12, 1927. Serial No. 232,833.

An object of my invention is to provide a novel rotary underreamer in which a new cutting edge is constantly presented to the surface to be cut.

5 Another object is to provide an underreamer in which the various superimposed cutters are all expanded or retracted by the action of one or more of the cutters.

10 A further object is to provide an underreamer which is positively closed as it moves upwardly into the casing.

A still further object is to provide an underreamer in which dirt, sand, and the like are effectively prevented from getting into 15 the moving parts thereof.

Other objects, advantages and features of invention may appear in the accompanying drawings, the subjoined detailed descriptions, and the appended claims.

20 In the drawing—

Figure 1, is a side elevation of my reamer.

Figure 2, is a longitudinal sectional view of the same.

25 Figure 3, is a sectional view taken on line 3—3 of Figure 2.

Figure 4, is a side elevation of the inner cutter sleeve.

Figure 5, is a side elevation, partly in section, of the inner sleeve.

30 Figure 6, is a plan view of the same.

Figure 7, is a side elevation, partly in section, of the bearing ring.

Figure 8, is a plan view of the same.

35 Figure 9, is a plan view of a modified form of sleeve.

Figure 10, is a side elevation of the same.

Referring more particularly to the drawing, my underreamer comprises a head 1, to which the drill pipe is secured, by a suitable 40 means such as a threaded box or pin, a tubular mandrel 2, is secured to and depends from the head 1. It is obvious that the mandrel may be integral with the head or may be threaded therein as desired. A plurality of 45 superimposed cutter elements 3, are mounted

on the mandrel 2, and these elements being identical in construction only one will be discussed in detail.

A sleeve 4, is eccentrically mounted on the mandrel 2, and is keyed thereto by a key 50 5, which extends longitudinally of the mandrel and the various sleeves, being provided with a slot into which the key enters.

The stationary sleeves are positioned at different angles to each other so that the cutting surfaces will be engaging the hole at various points throughout the 360 degrees of arc. This is more clearly brought out through examination of Figure 3.

55 A ring 6, is rotatably mounted upon the sleeve 4, and eccentrically positioned on the sleeve, and the ring is so arranged as to only partially rotate on the sleeve.

A flange 7, is formed on the top of the sleeve 4, against which the ring 6, rests, thus limiting the upward movement of the ring. The sleeve 4, is provided with vertically extending key 8, which engages a shoulder 9, in the ring 6, thus limiting the rotary movement of the ring.

70 A plurality of horizontally extending and arcuate lugs 10, are formed in the sleeve 4, and terminate in the key 8. These lugs are adapted to enter arcuate ways 11, in the ring 6, when the ring is in the extended or cutting position, thus preventing longitudinal movement of the ring along the mandrel and add great strength and rigidity to the cutters. In order to remove the ring from the sleeve a cut 12, is provided in the ring of sufficient 75 width to accommodate the lugs 10, so that when the lugs are moved into the cut the ring may be slipped downwardly off of the sleeve.

80 A cutter ring 13, is journaled on the ring 6, and rotates during the cutting operation of the tool. The exterior surface of the cut ring is provided with suitable cutting teeth to suit the particular needs of the formation in which the reamer is operated.

85 A flange 14, at the top of the ring 6, limits

the upward movement of the cutter ring. A plate 15, rests against the bottom of the ring 6, and projects beyond the edge thereof, thus providing a bottom bearing for the cutter ring 13, and serves to hold the last named ring in operative position. The plate 15, is held in position on the tool by the flange 7, of the next adjacent cutter, the lowermost plate being held by a collar 16, which is held in place by a locked nut 17, and a nut 18. The nuts 17, 18, screw onto the bottom of the mandrel 2, and serve to hold the cutters in position on the mandrel.

If desired, a packing ring 19, may be provided on the inner surface of the ring 6, to prevent foreign matter from entering the journals of the cutters.

In removing the tool from the well, if the cutters will not of themselves move into retracted position when the drill pipe is reversed in rotation, I provide a spiral cam 20, which extends upwardly from the uppermost ring 6, and engages the bottom edge of the casing, to rotate the uppermost cutter into retracted position. Each successive lower cutter is then moved into a retracted position by coacting lugs 21, 22, on the lower and upper surfaces respectfully, of the adjacent rings 6, which lugs engage and cause the retraction of all of the cutters, thus the tool is readily removed from the hole.

If desired, the rotating cutting ring 13, may be dispensed with and cutters provided on the ring 6, as shown in Figures 9, 10, the ring 6' is provided with extending cutter teeth 23, on the high side thereof, so that a cutting action is had during the rotation of the tool.

As previously stated, the mandrel 2, is hollow, and the nut 18 is provided with a bore 24, through which the drill mud passes to provide circulation in the hole. Any other desirable means may be provided for the circulation of the drilling mud, and ports 45 may be provided at various points for the emission of the mud.

Having described my invention, I claim:

1. A rotary underreamer comprising a mandrel, a plurality of superimposed cutter elements on said mandrel, and a cutter ring rotatably mounted on each of said cutter elements, and coacting means on each of the adjacent cutter elements whereby said cutter elements are all extended or retracted together.

2. A rotary underreamer comprising a head, a mandrel depending from the head, a plurality of cutters on said mandrel, each of said cutters comprising a ring, partially 60 rotatable on the mandrel and a cutter ring rotatably mounted on said first named ring, means on the upper cutter adapted to be engaged by the casing when the reamer is removed from the hole whereby said cutter 65 is moved to a retracted position, and means

on adjacent cutters adapted to coact and move said cutters to retracted position.

3. A rotary underreamer comprising a head, a mandrel depending from the head, a sleeve keyed to the mandrel, said sleeve eccentrically mounted on the mandrel, a ring partially rotatable on the sleeve and eccentrically mounted thereon, and a cutter ring rotatably mounted on said first named ring, means on the upper cutter adapted to be engaged by 75 the casing when the reamer is removed from the hole whereby, said cutter is moved to a retracted position, and means on the adjacent cutters adapted to coact and move said cutters to retracted position. 80

4. A rotary underreamer comprising a head, a mandrel depending from the said head, a sleeve keyed to the mandrel and eccentrically mounted thereon, a ring eccentrically mounted on the sleeve and partially rotatable thereon, a vertical key on the sleeve, and a shoulder on the ring adapted to be engaged by the key to limit the rotation of the ring, horizontal lugs on the sleeve, said ring having slots therein to receive the lugs 90 when the ring is in extended position.

5. A rotary underreamer comprising a head, a mandrel depending from the head, a plurality of superimposed cutter units on the mandrel, each cutter unit comprising a 95 sleeve keyed to the mandrel and eccentrically mounted thereon, a ring, eccentrically mounted on the sleeve and partially rotatable thereon, a key in the sleeve, a shoulder on the ring whereby rotation of the ring is limited, lugs 100 on the sleeve, said ring having slots to receive the lugs when the ring is in extended position, said ring having a cut thereon to accommodate the lugs when in the retracted position, whereby the ring may be removed 105 from the sleeve and a cutter ring rotatably mounted on said first named ring.

6. A rotary underreamer comprising a head, a mandrel depending from the said head, a sleeve keyed to the mandrel and eccentrically mounted thereon, a ring eccentrically mounted on the sleeve and partially rotatable thereon, a vertical key on the sleeve, and a shoulder on the ring adapted to be engaged by the key to limit the rotation of the ring, means on the upper cutter adapted to be 115 engaged by the casing, when the reamer is removed from the hole whereby said cutter is moved to a retracted position, and means on adjacent cutters adapted to coact and move said cutters to retracted position. 120

7. A rotary underreamer comprising a head, a mandrel depending from the said head, a sleeve keyed to the mandrel and eccentrically mounted thereon, a ring eccentrically mounted on the sleeve and partially rotatable thereon, a vertical key on the sleeve, and a shoulder on the ring adapted to be engaged by the key to limit the rotation of the ring, means on the upper cutter adapted to 125 130

be engaged by the casing, when the reamer
is removed from the hole whereby said cutter
is moved to a retracted position, and
means on adjacent cutters adapted to coact
5 and move said cutters to a retracted position,
said means comprising a spiral cam se-
cured to the uppermost ring, and lugs ex-
tending from the adjacent ring adapted to
engage the simultaneous moving of the rings.

10 In testimony whereof I affix my signature.

SWAN M. AKEYSON.
